(57) **CLAIM**

The ornamental design for a drill brush attachment, as shown and described.

DESCRIPTION

FIG. 1 is a front view of a drill brush attachment showing my new design;

FIG. 2 is a rear view of the drill brush attachment;

FIG. 3 is a right side view of the drill brush attachment;

FIG. 4 is a left side view of the drill brush attachment;

FIG. 5 is a top view of the drill brush attachment;

FIG. 6 is a bottom view of the drill brush attachment; and,

FIG. 7 is a top front side perspective view of the drill brush attachment shown in an environment of use.

The broken lines in FIG. 7 are illustrative of environmental structure forming no part of the claimed design.

1 Claim, 7 Drawing Sheets
